LIQUID HEATER CONTROL

Ray C. Newhouse, Wauwatosa, Wis.

Application November 23, 1942, Serial No. 466,605

3 Claims. (Cl. 236—33)

The present invention relates generally to improvements in the art of heating, and relates more specifically to improvements in the construction and operation of automatic control mechanism for water heaters or the like.

Generally defined, an object of this invention is to provide an improved mechanically actuated control system for water heaters or the like, which is simple in construction and reliable in use.

In my prior Patent No. 2,303,382, dated December 1, 1942, I have disclosed an improved intermittently operable fuel burning automatic water heater in which the fuel supply is controlled by means of superimposed temperature responsive devices or thermostats which are acted upon by upper and lower strata of the hot water in a confining zone, to operate a fuel control valve through a system of electrical connections and magnets. While this patented liquid heating system is entirely practical and satisfactory in operation, it is rather complicated and cannot be used where no electricity is available for actuation of the fuel control valve; and it is far more desirable to have such a system motivated by mechanisms forming part of the unit itself without necessitating the use of outside sources of power.

It is therefore an object of the present invention to provide an improved liquid heating system or unit of the fuel burning type, wherein the fuel supply is most effectively controlled by simple mechanism which is actuated by the temperature of the liquid within the storage zone of the unit.

Another specific object of this invention is to provide a simple fuel burning water heater adapted to utilize fluent fuels such as gas, and which besides conserving fuel is highly dependable in action.

A further specific object of my present invention is to provide a new and useful water heating system which requires minimum attention while insuring an abundant supply of hot water at all times.

Still another specific object of the invention is to provide improved valve actuating mechanism which is especially and advantageously applicable to a water heating system of the fuel burning type.

These and other specific objects and advantages of the invention will be apparent from the following detailed description.

A clear conception of a practical embodiment

of the present improvement, and of the mode of constructing and of operating a fuel burning water heating system built in accordance with the invention, may be had by referring to the drawing accompanying and forming a part of this specification wherein like reference characters designate the same or similar parts in the various views.

Fig. 1 is a somewhat diagrammatic view of 10 one of the improved fuel burning liquid heating systems, central vertical sections having been taken through the heater and through the liquid storage tank;

Fig. 2 is an enlarged side elevation of the main 15 fuel control valve showing part of the improved actuating mechanism;

Fig. 3 is a similarly enlarged front elevation of the main fuel control valve showing more of the improved actuating mechanism;

Fig. 4 is an enlarged diagram of the fuel control 20 valve showing the same fully opened by the upper thermostat associated with the liquid storage chamber;

Fig. 5 is a similar diagram of the fuel control 25 valve showing the upper thermostat inactive and the lower thermostat in action as when closing the valve; and

Fig. 6 is another similar diagram showing the valve fully closed by the lower thermostat.

While the invention has been shown and described herein by way of illustration, as being embodied in an automatic gas burning water heater wherein the main fuel supply is controlled by upper and lower thermostats associated with a water supply and storage tank, it is not my desire or intent to unnecessarily restrict the scope or utility of the improvement by virtue of this specific embodiment.

Referring to the drawing, the fuel burning 40 water heating system shown therein, comprises in general a liquid storage tank 8 having a lower fresh or cold water inlet pipe 9 and an upper hot water outlet pipe 10 and preferably being covered with a jacket 11 of insulation surrounding its 45 storage chamber 12; a fuel burning heater 13 having a burner 14 adapted to be supplied with fluent fuel from a fuel supply line 15 past a shut-off valve 16 and an automatic control valve 17, and being provided with a liquid circulating 50 and heating coil 18 having its lower and upper ends in open communication respectively with lower and upper portions of the storage chamber 12; upper and lower temperature responsive devices or thermostats 19, 20 respectively exposed 55 to the medial and lowermost portions of the

storage chamber 12; and mechanical actuating mechanism operatively connecting the thermostats 19, 20 with the main fuel control valve 17.

The storage tank 8 is preferably of considerable capacity and relatively high, and the heater 13 may be of any conventional type of fuel burner and is preferably located closely adjacent to the tank 8. The cold water inlet pipe 10 communicates with the storage chamber 12 beneath a spreader 21, and the hot liquid outlet pipe 10 is preferably disposed within the insulating jacket 11 as shown. The heater 13 is provided with an exhaust gas stack 22, and this type of heater is ordinarily provided with a pilot light 23 which is connected to the fuel supply line 15 in advance of the shut-off valve 16.

As previously indicated, the upper temperature responsive device or thermostat 19 is associated with the medial portion of the storage chamber 12 considerably above the cold liquid inlet 9, while the lower temperature responsive device or thermostat 20 is associated with the bottom of the chamber 12; and these thermostats 19, 20 are of well known construction as shown and described in U. S. Patent No. 747,297, granted December 15, 1903. The upper thermostat 19 has an external end lever 24, and the lower thermostat 20 has an external end lever 25, these levers 24, 25 being adapted to revolve about the central longitudinal axes of the respective thermostats 19, 20 when they are subjected to varying temperatures within their corresponding upper and lower zones within the chamber 12. As viewed in Fig. 3, both of the levers 24, 25 are adapted to rotate in counter-clockwise directions when the corresponding thermostats 19, 20 are subjected to diminishing temperatures, while both levers 24, 25 will rotate in clockwise directions when the thermostats 19, 20 are subjected to rising or increasing temperatures.

The improved fuel control valve 17 is shown in detail in Figs. 2 to 6 inclusive, and comprises an outer casing 26 having a plug valve member 27 oscillatable therein by means of an external stem 28, the casing being provided with a bracket 29 for suspending the valve 17 from the tank 8. A collar 30 is rigidly attached to the stem 28 intermediate its ends, and this collar 30 carries a pin 31 which is disposed parallel to but eccentrically of the stem 28. A lever 32 is freely rotatably suspended from the valve stem 28 on one side of the collar 30 and has a lug 33 which is cooperable with one side of one overhanging end of the pin 31, and a similar lever 34 is likewise freely rotatably suspended from the valve stem 28 on the opposite side of the collar 30 and is provided with a lug 35 which is cooperable with the opposite side of the other overhanging end of the pin 31. The swinging end of the lever 32 is connected to the swinging end of the upper thermostat lever 24 by means of a link 36, while the swinging end of the lever 34 is likewise connected to the swinging end of the lower thermostat lever by a similar link 37. In practice, it may be desirable to make the connections or links 36, 37 adjustable in length in an obvious manner, and it is to be noted that the mechanism is such that either thermostat 19, 20 may actuate the fuel control valve member 27 independently of the other; and that when the pin 31 is swung to its extreme position toward the left as in Figs. 3 and 4, the valve port or passage 38 will be fully opened, whereas opposite extreme positioning of the pin 31 will result in closing of the valve passage 38, see Fig. 6.

During normal operation of the improved fuel

burning liquid heating system, the inlet pipe 9 will be connected to a suitable source of fresh water supply, the warm water outlet pipe 10 will be connected to one or more zones of hot water utilization, the shut-off valve 16 will be open, and the pilot light 23 will be ignited. The thermostats 19, 20 should be adjusted to the temperature desired, and when warm water is withdrawn from the outlet pipe 10, cold water will obviously be admitted to the bottom of the chamber 12 through the inlet pipe 9. As the admitted cold water contacts the lower thermostat 20, it causes the lever 25 thereof to swing in a counter-clockwise direction as viewed in Figs. 3 to 6 inclusive, and to thereby swing the lug 35 to the extreme left away from the valve actuating pin 31, but will not move the valve member 27. The admitted cold water will then continue to rise in the chamber 12 as the withdrawal of warm liquid from the pipe 10 continues; and when the cold water reaches the upper thermostat 19, it causes the lever 24 thereof to likewise swing in a counter-clockwise direction from the position of Fig. 3, thereby swinging the lug 33 to the left and moving the pin 31 so as to swing the valve member 27 with its port 38 in open communication with the fuel supply pipe 15, that is, to open the valve 17 as shown in Fig. 4.

As soon as the valve 17 is thus opened, the heater 13 will function to circulate liquid from the chamber 12 through the pipe 18 and will raise the temperature of the water, and the valve 17 will remain open while the heater will continue to operate as long as hot liquid is being withdrawn through the outlet pipe 10. The heater 13 need be of sufficient capacity only to heat the liquid to the desired temperature, and so that the liquid being heated plus the heated liquid already stored above the upper thermostat 19 will always provide an abundant supply of hot water; and as the water in contact with the thermostat 19 becomes heated, the lever 24 will swing in a clockwise direction and the corresponding lug 33 will move toward the right as shown in Fig. 5, thereby avoiding interference with the subsequent action of the lug 35. As the heating of the liquid continues, warm water will eventually reach the lower thermostat 20, whereupon the lever 25 will be swung in a clockwise direction thereby moving the lug 35 toward the right as in Fig. 5 and shifting the valve member 27 into closed position, as shown in Fig. 6. Since the heater 13 is of relatively small capacity, it should preferably be acting at full capacity whenever it is functioning.

Subsequent or continued withdrawal of hot water through the outlet pipe 10, or prolonged delay in withdrawal of warm water resulting in gradual natural cooling of the liquid in the chamber 12 by radiation, will again cause the lower and upper thermostats 20, 19 to be successively subjected to cool liquid and will result in successive movements of the lugs 35, 34 of these two thermostats toward the left, and consequent repetition of the heating cycle. It is to be noted, however, that the upper thermostat 19 functions only to open the fuel supply valve 17 when the cold water reaches this thermostat, and that the lower thermostat 20 functions only to close the valve 17 when the warm liquid completely fills the chamber 12; and that these two temperature responsive devices operate independently of each other and without in any manner interfering with the normal operation of each other. If no hot water is needed for a prolonged period of time, the heater 13 may be shut off by closing the valve

16, but if automatic operation at any time is still desired, the valve 16 may be left open and the lower thermostat 20 may be adjusted to function at higher temperatures. The location of the thermostats 19, 20 with the upper thermostat above the lower but still considerably beneath the upper outlet end of the chamber 12, is desirable so that an abundant supply of hot water will always remain above the thermostat 19 when the system is functioning normally; and these thermostats 19, 20 are the sole means for insuring normal automatic operation of the heating unit.

From the foregoing detailed description it will be apparent that the present invention provides an improved automatic fuel burning liquid heating system which is extremely simple and compact in construction and which is moreover highly efficient and reliable in operation. The improved system does not depend upon any outside sources for its operation, and can be installed in the form of a simple compact unit which will continue to function as long as the fuel supply remains uninterrupted. The improved control valve mechanism besides being simple and compact, is also durable and embodies no complicated parts which are apt to interfere with the normal operation of the valve, and the desired temperatures may be readily varied to suit conditions by merely making proper adjustments of the thermostats 19, 20. The simplicity of the mechanism permits manufacture and sale thereof at moderate cost, and also permits most efficient operation of the improved systems at maximum efficiency and with minimum fuel consumption.

It should be understood that it is not desired to limit this invention to the exact details of construction or to the precise mode of use, herein shown and described, for various modifications within the scope of the claims may occur to persons skilled in the art.

I claim:

1. In combination, a vertically elongated liquid storage chamber having a lower liquid inlet and an upper liquid outlet, a fuel burning heater hav-

ing a liquid circulating duct communicating with lower and upper portions of said chamber and also having a fuel supply line provided with a fuel control valve, an upper thermostat operable by cool liquid rising into the medial upper portion of said chamber to effect opening of said valve, a lower thermostat operable by warm liquid descending into the lower portion of said chamber to effect closing of said valve, and a mechanical motion transmitting connection interposed directly between each of said thermostats and said valve.

2. In combination, a vertically elongated liquid storage chamber having a lower liquid inlet and an upper liquid outlet, a fuel burning heater having a liquid circulating duct communicating with lower and upper portions of said chamber and also having a fuel supply line provided with a fuel control valve, an upper thermostat operable by cool liquid rising into the medial upper portion of said chamber and coacting with an abutment to effect opening of said valve, and a lower thermostat operable by warm liquid descending into the lower portion of said chamber and coacting with another abutment to effect closing of said valve, said abutments being interchangeably co-operable with said valve to move the same in opposite directions.

3. In combination, a vertically elongated liquid storage chamber having a lower liquid inlet and an upper liquid outlet, a fuel burning heater having a liquid circulating duct communicating with lower and upper portions of said chamber and also having a fuel supply line provided with a fuel control valve, an upper thermostat operable by cool liquid rising into the upper medial portion of said chamber and having direct mechanical coaction with said valve to effect opening thereof, and a lower thermostat operable by warm liquid descending into the lower portion of said chamber and also having direct mechanical coaction with said valve to effect closing thereof.

RAY C. NEWHOUSE.
